TEMPERATURE REGULATING APPARATUS

Filed May 22, 1928

Inventor:
John H. Payne,
by Charles E. Tullar
His Attorney.

UNITED STATES PATENT OFFICE

JOHN H. PAYNE, OF BALLSTON SPA, NEW YORK, ASSIGNOR TO GENERAL ELECTRIC COMPANY, A CORPORATION OF NEW YORK

TEMPERATURE-REGULATING APPARATUS

Application filed May 22, 1928. Serial No. 279,812.

My invention relates to temperature regulating apparatus, and has for its principal object the provision of an improved apparatus and method of operation whereby the 5 temperature of a chemical solution, or other body, may be maintained substantially constant without sparking at the contacts through which the supply of heating current is controlled.

10 Difficulty is frequently encountered due to sparking at the contacts of a heat responsive element utilized to regulate the heating current of a body which is required to be maintained at a substantially constant temperature. Thus in the manufacture of piezo electric crystals from a chemical solution, for example, injurious sparking between the contacts of the heat responsive element is likely to prevent the fine degree of temperature regulation which is required for the proper growth of the crystal. In accordance with my invention, this difficulty is avoided by the provision of an improved temperature regulating apparatus including a space discharge 15 device which has its grid potential controlled in accordance with the temperature of the body to be heated.

20 My invention will be better understood from the following description when considered in connection with the accompanying drawing and its scope will be pointed out in the appended claims.

25 The drawing diagrammatically illustrates a temperature regulating apparatus wherein my invention has been embodied.

30 This apparatus comprises a heating element 1 located within a vessel 2 and arranged to be connected to a suitable source of heating current through switches 3 and 4 and supply terminals 5. The switch 3 is biased to 35 its open position by a spring 6 and is provided with a closing coil 7 which is arranged to be connected to the supply leads 5 through the switch 4, a space discharge device 8 and a pair of resistors 9 and 10. The space discharge device 8 includes an anode 11, a cathode 12, and a grid 13 which is connected to the cathode 12 through impedance devices shown as a resistor 14 and resistor 10. The 40 grid potential of the device 8 is controlled

by a heat responsive element 15 mounted in the vessel 2 and provided with a solid contact 16 and a liquid contact 17 which assumes a position dependent on the temperature within the vessel 2.

45 Assuming the current supply terminals 5 to have the polarities indicated in the drawing, sufficient current is transmitted through the device 8 to close the switch 3 only when the contacts 16 and 17 of the heat responsive element 15 are disengaged from one another. Thus when the contacts 16 and 17 are disengaged from one another the grid 13 is connected to the positive terminal through the resistor 14 and tends to assume a positive potential with respect to the cathode. When the contacts 16 and 17 are in engagement with one another, however, the resistor 14 is connected between the supply terminals 5 with the grid at the negative terminal and insufficient current to operate the switch 3 is transmitted through the device.

50 When the grid 13 is connected to the positive supply terminal through the resistor 14, it is subjected to a positive bias potential of 55 a magnitude dependent on the potential drop produced in the resistor 10 by the cathode heating currents of the device 8. When the grid 13 is connected to the negative supply terminal through the device 15, it is subjected to a negative bias potential dependent on the potential drop produced in the resistor 9 by the cathode heating current. These bias potentials are of advantage in that 60 they tend to maintain the current of the device 8 at a value which is either slightly above or below that required to operate the switch 3 so that the switch 3 is very sensitive to change in the relation between the contacts of the heat responsive element 15.

65 It has been found that the resistance of resistor 14 should be made fairly high in order to prevent sparking at the contacts of the device 15. The particular value of resistance 70 to be used in each case will of course depend on the electrical constants of the other parts of the apparatus. In the practical operation of the apparatus, a resistance of one to ten thousand ohms has been found satisfactory.

What I claim as new and desire to secure by Letters Patent of the United States is:

1. The combination of a heat producing element, a switch provided with an operating coil and arranged to transmit heating

5 current to said element, a space discharge device provided with a cathode and an anode for transmitting operating current to said coil and with a grid for controlling said operating current, means in circuit with said cathode providing a positive and a negative biasing potential with respect to said cathode, means including a resistor for applying one of said biasing potentials to said grid, and
10 means including a contact and closure means therefor operable in response to the heat produced by said heating element for applying the other of said biasing potentials to said grid.

20 2. The combination of a heat producing element, electrical current supply terminals, a switch provided with an operating coil and arranged to interconnect said element with said terminals, a space discharge device provided with a cathode and anode connected between said terminals through said operating coil and with a grid, an impedance device connected between said grid and one of said terminals, and a circuit control device operated in accordance with the heat of said element and connected between said grid and the other of said terminals.

25 3. The combination of a heat producing element, means for controlling the supply of heating current to said element, a space discharge device arranged to control the energization of said control means and provided with a grid for controlling the current transmitted between its cathode and anode, terminals for supplying heating current to said cathode, an impedance device connected between said grid and one of said terminals, and a circuit control device arranged to operate in accordance with the heat of said element and connected between said grid and the other of said terminals.

40 4. The combination of a space discharge device provided with a cathode and an anode and with a grid for controlling the current transmitted between said cathode and anode, a pair of terminals for supplying heating current to said cathode, an impedance device connected between said grid and one of said terminals, and a circuit control device connected between said grid and the other of said terminals.

45 5. The combination of a space discharge device provided with a cathode and an anode and with a grid for controlling the current transmitted between said cathode and anode, a pair of terminals for supplying heating current to said cathode, impedance devices each connected between said cathode and a different one of said terminals, an impedance
55 device connected between said grid and one

of said terminals, and means arranged to connect said grid to the other of said terminals.

In witness whereof, I have hereunto set my hand this 21st day of May, 1928.
